[57] CLAIM

The ornamental design for a foil wrapped candy ornament, as shown and described.

DESCRIPTION

FIG. 1 is a perspective view of a foil wrapped candy ornament showing my new design;

FIG. 2 is a right side elevational view thereof, the opposite side being a mirror image;

FIG. 3 is a front elevational view thereof;

FIG. 4 is a rear elevational view thereof;

FIG. 5 is a top plan view thereof; and,

FIG. 6 is a bottom plan view thereof.

The candy inside the foil is not part of the claimed design.
